- (35) 2-trichloromethyl-4-morpholino-6-(2-acetamidoethylamino)-s-triazine
- (36) 2-trichloromethyl-4-morpholino-6-(2-(morpholino)ethyl)-s-triazine

Compositions according to the present invention also comprise a pharmaceutical carrier which may either be solid material or a liquid. Preparations for oral administration can be liquids or solids or any combination of these forms, such as syrups, elixirs, powders, capsules, or tablets. Preparations for administration of the active agent in unit dose form can be powders, compressed tablets, or a powder enclosed in a suitable capsule of absorbable material such as gelatin. The powders or compressed tablets may also comprise suitable excipients and/or diluents such as starch, lactose, stearic acid, magnesium stearate, dextrin or polyvinylpyrrolidone.

Preparations for topical application may be in the form of a liquid, a powder, a salve, or as an aerosol.

Preparations for parenteral administration may be sterile solutions or suspensions in liquids such as water, physiological saline, benzyl alcohol, ethyl oleate, methylcellulose, dimethyl sulfoxide or other liquid excipients known in the pharmaceutical and veterinary formulation art.

Any of the above preparations may contain the triazines of the invention or may contain in addition other pharmaceutically active agents. For example, for topical

application it may be desirable to include a germicide and/or a fungicide.

The unit dosage or therapeutically effective quantity of the triazines used according to this invention as analgesics, muscle relaxants, anticonvulsants and/or tranquilizers can vary over wide limits. For oral or parenteral administration in some cases, as little as 0.01 milligram of the active material per kilogram of body weight can be effective in the reduction of pain or in effecting sedation and muscle relaxation, while seldom will a dosage in excess of about 500 milligrams per kilogram of body weight be required. In general, for oral administration, the effective dosage will be from about 1.0 to 200 milligrams per kilogram of body weight, while for parenteral administration, the effective dosage will be from about 0.10 to about 100 milligrams per kilograms of body weight. Each dosage unit form—each capsule, tablet, ampoule, or prescribed dose—can contain from about 1 percent to about 95 percent of active material, based upon the total weight of the formulation and preferably contains from about 2.5 percent to about 50 percent of the active material, on the same basis. Of course, it is possible to administer the therapeutics without the use of a pharmaceutical carrier.

The therapeutic agents used according to the invention can be administered either prior to or after the onset of the condition to be treated, such as when they are used as: analgesics for the amelioration of pain; motor depressants or tranquilizers to relieve nervous tension; central depressants to reduce hyperexcitability and induce sedation, or as muscle relaxants for relief from pain and discomfort of disorders involving muscle spasms.

Preparation

The s-triazines of this invention can be prepared by conventional methods known in the art for preparing these types of s-triazines. The following descriptions are illustrative of some of the methods that may be used.

The starting material for most of the s-triazines of this invention is 2,4,6-tris-trichloromethyl-s-triazine. From this s-triazine the various compounds of the invention are prepared by replacement of the trichloromethyl groups with the various groups depicted in Formula I.

Thus, the morpholino, piperazino and N-hydroxyalkyl and N-alkyl piperazino substituents are introduced by reacting the appropriate trichloromethyl-s-triazine with an equimolar amount of morpholine, piperazine, N-hydroxyalkyl piperazine or N-alkyl piperazine in a solution of a lower alkanol at moderate temperatures. By reaction of the piperazino-s-triazine in dioxane with the appropriate chloroalkyl benzene,

R is alkylene), in the presence of pyridine, the phenylalkyl group

is introduced. Likewise reaction of the piperazino s-triazine in a solution of acetic acid with KOCl introduces the carbamoyl R group. The corresponding N-hydroxyalkylcarbamoyl group is introduced by first preparing the N-ethoxycarbonyl piperazino s-triazine by reacting the piperazino s-triazine, dissolved in a halogenated hydrocarbon solvent, with Cl-C(O)OC₂H₅ in the presence of pyridine and then by reaction of this precursor in a lower alkanol solvent with the appropriate alkanolamine. The 2,2,2-trichloro-1-iminoethyl group is introduced by reacting the piperazino s-triazine with trichloroacetonitrile. The last Y substituent, -alkylene-

is introduced by reacting the N-hydroxyalkyl piperazino-s-triazine in a halogenated hydrocarbon diluent with the appropriate dicarboxylic acid anhydride.

Within the Z or third category of substituents the hydroxylamino group is introduced by replacement of a trichloromethyl group by reaction of the appropriate trichloromethyl-s-triazine with a hydroxylamino (H_2N -alkylene-OH) in the presence of a catalytic amount of an alkali metal alcoholate in a lower alkanol solvent at moderate temperatures.

The alkoxycarbonyloxyalkyl-s-triazines may be prepared by the methods described in U.S. 3,264,293. The s-triazines described therein are then used to prepare the s-triazines of this invention.

The hydrazino-s-triazines may be prepared by replacement of the trichloromethyl substituent by reacting the appropriate trichloromethyl-s-triazine at room temperature with a molar excess of hydrazine hydrate. Reaction of the appropriate hydrazino-s-triazine with a suitable ketone or aldehyde at moderate temperatures yields the alkylidene-hydrazino-s-triazine. Similar treatment with an aliphatic aldehyde

in a lower alkanol solvent yields the phenylalkylidene-hydrazino.

The s-triazines containing the

radical are readily prepared by reacting an appropriate hydroxylamino-s-triazine with the appropriate mono- or dicarboxylic acid anhydride, benzoyl chloride, alkenedioic acid anhydride, N,N-dialkylcarbamoyl chloride or mono alkyl ester of a dicarboxylic acid chloride

R is alkylene and R_1 is alkyl). The reaction of the mono- or dicarboxylic acid anhydrides with the appropriate hydroxylamino-s-triazine is preferably carried out in an ethyl acetate reaction media in the presence of triethylamine.

The alkylamino substituents are preferably introduced by reaction of the appropriate trichloromethyl-s-triazine in a lower alkanol solvent with a primary alkylamine.

The chloroalkylamino groups are introduced by conventional technique such as reacting an appropriate hydroxylamino-s-triazine with thionyl chloride.

The N,N-dialkylaminoalkoxy groups are introduced by reacting an appropriate trichloromethyl-s-triazine with an N,N-dialkylaminoalkanol in the presence of sodium hydroxide.

The α -hydroxyalkyl-s-triazines

may be prepared by reacting an alkoxycarbonyloxyalkyl-s-triazine in a lower alkanol solvent at the reflux temperature with a barium alkanolate prepared by reacting barium hydroxide in hot alkanol, preferably methanol, and separating the carbonate from the barium alkanolate.

The $-\text{NH-alkylene-NH-C}(\text{O})\text{alkyl}$ group may be introduced by replacement of a trichloromethyl group with an alkylendiamino group by reacting the trichloromethyl-s-triazine with a molar excess of an alkylene-diamine; and then reacting this aminoalkylamino-s-triazine with the appropriate alcanoic acid anhydride in the presence of pyridine.

The last group of s-triazines, those containing the morpholinoalkyl group may be prepared by reacting an alkenyl-s-triazine in a lower alkanol solvent with morpholine.

The salts of the s-triazines of the invention are prepared by the conventional method of reacting the s-tria-

zine with an inorganic or organic acid. Examples of such acids are sulfuric, phosphoric, hydrochloric, sulfamic, benzylsulfonic, maleic, fumaric, succinic, tartaric and the like. The salt-forming acid should be one that is physiologically acceptable for administration to mammals. The hydrochloride salts are preferred.

The following examples will serve to illustrate the preparation of the compounds of this invention.

EXAMPLE I

10 30 g. of 2,4-bis-trichloromethyl-6-morpholino-s-triazine were suspended in 200 ml. of methanol and 9.12 g. of ethanol amine and 0.5 g. of Na dissolved in 50 ml. of methanol added thereto. The mixture was heated under reflux until solution occurred (about 10 minutes) and such heating continued for about a further 50 minutes. The solution was cooled on ice, whereby 2-trichloromethyl-4-ethanolamino-6-morpholino-s-triazine crystallized out in almost analytically pure form. After it was filtered off, washed with water and dried, 22 g. of the product with a melting point of 162-164° C. were obtained. The yield was 86.3% of theory.

The starting material of this example was produced by dissolving 1 mol of tris-trichloromethyl-s-triazine in about 1 liter of methanol and adding 1 mol of morpholine to such solution at 10° C. Upon addition of the amine the solution warmed up to about 40-50° C. When the reaction solution cooled down the 2,4-bis-trichloromethyl-6-morpholino-s-triazine precipitated out and was filtered off and washed. The yield was about 75% of theory. The melting point was 160-165° C.

EXAMPLE II

15 178.5 g. (0.4 mol) 2-(1-methyl-1-(ethoxycarbonyloxy)ethyl)-4,6-bis-(trichloromethyl)-s-triazine was dissolved in 200 ml. of hot methanol and 35 g. (0.4 mol) of morpholine was added. After cooling, 128 g. of 2-(α -methyl- α -ethoxycarbonyloxy)-ethyl-4-morpholino-6-trichloromethyl-s-triazine, M.P. 106-109° C., was obtained.

EXAMPLE III

20 31.25 g. (0.1 mol) of 2-trichloromethyl-4-piperazino-6-hydrazino-s-triazine was heated at the reflux temperature for 1 hour with 10.6 g. (0.1 mol) of benzaldehyde in 300 ml. of methanol. After the methanol was distilled off and the residue washed with water, the product, 2-trichloromethyl-4-piperazino-6-benzylidenehydrazino-s-triazine, M.P. 185-190° C. was collected in 87.4% yield.

EXAMPLE IV

25 40 g. (0.1 mol) of 2-piperazino-4,6-bis-(trichloromethyl)-s-triazine was suspended in 90 g. hydrazine hydrate at room temperature for 2 days. The product, 2-trichloromethyl-4-piperazino-6-hydrazino-s-triazine, M.P. 167-169° C., was separated from the mixture and washed with water.

EXAMPLE V

30 34.15 g. (0.1 mol) of 2-trichloromethyl-4-piperazino-6-(2-hydroxyethylamino)-s-triazine was slowly added to a stirred mixture of 3.65 g. HCl gas in 300 ml. of methanol. After 2 hours, the crystals of 2-trichloromethyl-4-piperazino-6-(2-hydroxyethylamino)-s-triazine-hydrochloride, M.P. 210° C., were separated out and dried.

EXAMPLE VI

35 34.2 g. (0.1 mol) of 2-trichloromethyl-4-morpholino-6-ethanolamino-s-triazine were heated to 50° C. in 150 ml. of dried ethyl acetate together with 10.5 g. (0.105 mol) of succinic acid anhydride and 10.6 g. (0.105 mol) of triethylamine, whereupon solution occurred. After 30 minutes the reaction mixture was permitted to cool down and then shaken out with water whereupon the triethylamine salt went over into the aqueous phase. Upon adjustment of the pH of the aqueous solution to 4 the 2-tri-

chloromethyl-4-morpholino-6-(2-succinyl-oxyethylamino)-s-triazine is obtained in free acid form. After washing and drying the yield was 38 g. or 86% of theory (melting point 176-178° C.).

PREFERRED EMBODIMENTS

While the s-triazines of Formula I show some depressant effects in mammals, there are differences both quantitative and qualitative exhibited by individual members of the class. Especially preferred depressants because of their activity as analgesics, muscle relaxants, anticonvulsants, and/or tranquilizers are the s-triazine of the formula

(II)

wherein Y is

where R is hydrogen, alkyl of 1-3 carbon atoms, or hydroxylalkyl of 1-3 carbon atoms, preferably hydrogen, methyl or 2-hydroxyethyl, and

Z is $-\text{NHR}_1-\text{OH}$ where R_1 is alkylene of 1-4 carbon atoms, preferably $-\text{NHCH}_2\text{CH}_2-\text{OH}$,

or

¹ Numbers correspond to numbered triazines in Cols. 2 and 3.

² 32 mg./kg.

where alkyl is of 1-3 carbon atoms, preferably methyl;

where R_2 is carboxyalkyl of 2-5 carbon atoms, preferably carboxypropyl and alkylene is of 1-3 carbon atoms, preferably 2-methylethylene; or dialkylamino of 2-4 carbon atoms, preferably ethylamino; and salts thereof.

Preferred s-triazines within the subclass are:

- 2-trichloromethyl-4-morpholino-6-(2-hydroxyethylamino)-s-triazine,
- 2-trichloromethyl-4-morpholino-6-(2-hydroxypropylamino)-s-triazine,
- 2-trichloromethyl-4-piperazino-6-(2-hydroxyethylamino)-s-triazine, hydrochloride,
- 2-trichloromethyl-4-piperazino-6-benzylidenehydrazino-s-triazine,
- 2-trichloromethyl-4-(4-methylpiperazino)-6-hydrazino-s-triazine,
- 2-trichloromethyl-4-piperazino-6-hydrazino-s-triazine,
- 2-trichloromethyl-4-morpholino-6-(1-hydroxy-1-methylethyl)-s-triazine,
- 2-trichloromethyl-4-morpholino-6((carboxybutyryloxy)-2-methylethylamino)-s-triazine,
- 2-trichloromethyl-4-(4-(2-hydroxyethyl)-piperazino)-6-ethylamino-s-triazine,
- 2-trichloromethyl-4-piperazino-6-(2-hydroxyethylamino)-s-triazine, and
- 2-trichloromethyl-4-morpholino-6-(1,1-dimethyl-2-hydroxyethylamino)-s-triazine.

35 The following examples are presented to illustrate certain pharmacological responses induced by triazine compositions of the invention. These examples should in no way be regarded as limiting the scope of the invention.

40 The results of the various pharmacological responses tested are shown in Table I.

Analgesic response (a)

The presence of an analgesic effect was identified as an absence of a struggling or phonating response to a manual pinch of the tail of treated mice. The laboratory white mice for each treatment were placed in individual compartments. The mice were orally intubated with the test compound at the dosage of 500 milligrams per kilogram, and 15 minutes, 1 hour, 2 hours, 4 hours and 24 hours after treatment a pinch of the tail was applied to each mouse. Any compound inducing an analgesic response in 50 percent of the mice at any of these test intervals was considered active in this test. Some of the compounds were tested at lower dosages.

While the exact safety factor has not been evaluated for all compounds of the invention, it has been found that the effective analgesic dose of the triazines of the invention is considerably lower than the toxic dose (LD_{50}).

Muscle relaxant response (b)

As in (2) above, mice were orally intubated with the test compound and the muscle relaxant effects of the compounds were evaluated. The procedure for assessing skeletal muscle relaxant activity involves an evaluation of passivity, flaccidity and pinnal reflex blockage. Passivity is defined as an absence of the struggle behavior of the animal when manipulated manually and may indicate skeletal muscle relaxation, central depression, tranquilization, paralysis, or anesthesia. Flaccidity is measured by the decreased tonus of skeletal musculature and may indicate myorelaxant activity, central depression, or paralysis. The pinnal reflex is tested by touching the inner aspects of the ear with a fine wire to elicit a characteristic ear twitch. An impairment of this reflex suggests an inhibition of polysynaptic reflexes.

Analgesic response—intraperitoneal (c)

The analgesic response was determined in laboratory white mice by injection of the triazines under test at an intraperitoneal dosage of 100 mg. per kg. The results were obtained by evaluation similar to that described for the Approximate Analgesic Dose—Oral. The compounds were rated on a one plus (+) to four plus (++++) scale. When 1-2 mice out of ten showed an analgesic response, a + rating was assigned; ++ indicated that 3-6 out of ten mice responded; +++ indicated that 7-9 out of ten responded; while a ++++ rating meant that all ten mice gave an analgesic response at the dosage tested.

Muscle relaxant—tranquilization response (d)

The muscle relaxant effects, as expressed by passivity, flaccidity and pinnal reflex blockage, were assessed in laboratory mice injected intraperitoneally with 100 mg./kg. of the test compound as in (b). In addition the tranquilizing effects of the compounds under test were evaluated by the pernicious preening test (Wilfond, J. G. et al. Fed Proc. 19:20, 1960). The pernicious preening behavior was elicited by painting the rear of the mice with a pilocohesive dye. A violent unremitting tearing of the stiff, cohering strands of hair constitutes the pernicious preening behavior. Thirty minutes after injection, the pilocohesive dye was applied and the presence or absence of the compulsive behavior was noted for a 10 minute interval. The ratings for the muscle relaxant response are based upon the scale given in (c). Effective antagonism of pernicious preening is shown with the same scale as in (c). That is, + = 1-2 mice out of ten, ++ = 3-6 mice out of ten, +++ = 7-9 mice out of ten and ++++ = 10 mice out of ten responded. Some of these values for the individual triazines were determined at a dosage of 32 mg./kg. while the others were determined on the basis of ED_{50} values, the dose at which 50 percent of the treated animals exhibit an effective response. These ED_{50} values were then trans-

50

55

60

65

70

75

lated into the +1 to +4 scale by the following criteria: ED_{50} values of 30-100 mg./kg. = +, 10-30 mg./kg. = ++, 3-10 mg./kg. = +++ and < 3 mg./kg. = +++++.

Anticonvulsant response (e)

The test procedures used were maximal electroshock and antistrychnine assay methods. The test compound was intraperitoneally injected into laboratory mice and after 30 minutes the anticonvulsant activity was measured. The technique employed in the maximal electroshock method was essentially that of Swinyard, E. A., J. Amer. Pharm. Assoc. 38:201 (1949). The mice were subjected to an alternating current stimulus, about equal to three times the current necessary to produce maximal seizures, and prevention of the hindlimb tonic extensor phase was considered to be an effective anticonvulsant action. In the antistrychnine assay, the mice were intraperitoneally injected with the test compound and then were challenged with a lethal intraperitoneal dose of strychnine sulfate. Increase in survival time against the lethal action of strychnine of greater than three standard deviations of the control means was considered an effective action. Anticonvulsant activity in these tests suggests skeletal muscle relaxation or efficacy against epileptic seizures. Effective antagonism of maximal electroshock seizure and antistrychnine activity are given on the same +1 to +4 scale as in (c). Some of these values for the individual triazines in the maximal electroshock seizure test were determined at a dosage of 100 mg./kg. while the others were determined on the basis of ED_{50} values, the dose at which 50 percent of the treated animals exhibited an effective response. These ED_{50} values were then translated into the +1 to +4 scale by the following criteria: ED_{50} values of 100-300 mg./kg. = +, 30-100 mg./kg. = ++, 10-30 mg./kg. = +++ and < 10 mg./kg. = +++++. The antistrychnine activities for the individual triazines were also determined in either of two ways. Some are based on the response ratio at 180 mg./kg. while the others on the ED_{50} values. The criteria for translating the ED_{50} values to the +1 to +4 scale is the same as for the maximal electroshock seizure test.

We claim as our invention.

1. A depressant veterinary and pharmaceutical composition comprising a

(a) compound of the formula

wherein Y is

wherein R is hydrogen; alkyl of 1-3 carbon atoms; hydroxyalkyl of 1-3 carbon atoms;

where m is 1-3;

wherein R' is hydrogen or hydroxyalkyl of 1-3 carbon atoms;

where alkylene is alkylene of 1-3 carbon atoms; and Z is $-\text{NH-alkylene-OH}$ where alkylene is alkylene of 1-4 carbon atoms;

where alkylene is alkylene of 1-4 carbon atoms and alkyl is alkyl of 1-3 carbon atoms;
 $-\text{NH}-\text{N}=\text{CR}_2\text{R}_3$ where R_2 is hydrogen or alkyl of 1-3 carbon atoms and R_3 is alkyl of 1-3 carbon atoms, phenyl or nitrophenyl;

where R_4 is carboxyalkyl of 2-5 carbon atoms, alkyl of 1-3 carbon atoms, phenyl, carboxy- α -alkenyl of 3-5 carbon atoms, dialkylamino of 2-6 carbon atoms or alkoxy carbonylalkyl of 3-7 carbon atoms and alkylene is alkylene of up to 3 carbon atoms;
 $-\text{NH-alkyl}$ where alkyl is alkyl of 1-3 carbon atoms;
 CCl_3 ;
 $-\text{NH-alkylene-Cl}$ where alkylene is alkylene of 1-3 carbon atoms; $-\text{O-alkylene-N-(alkyl)}_2$ where alkylene and alkyl have from 1-3 carbon atoms;

where each alkyl is of 1-3 carbon atoms;

where alkylene and alkyl have from 1-3 carbon atoms; and

where alkylene is of 2-4 carbon atoms; and the salts thereof; and

(b) a physiologically acceptable carrier, the percent by weight of (a) in the total formulation being from about one to about 95.

2. The veterinary and pharmaceutical composition of claim 1 wherein Y is

where R is hydrogen, alkyl of 1-3 carbon atoms or hydroxyalkyl of 1-3 carbon atoms; and Z is $-\text{NHR}_1-\text{OH}$ where R_1 is alkylene of 1-4 carbon atoms;

where alkyl is of 1-3 carbon atoms;

where R_2 is carboxyalkyl of 2-5 carbon atoms and alkylene is of 1-3 carbon atoms; or dialkylamino of 2-4 carbon atoms; and salts thereof.

3. The veterinary and pharmaceutical composition of claim 2 wherein Y is

and Z is $-\text{NHR}_1\text{OH}$.

4. The veterinary and pharmaceutical composition of claim 3 wherein Z is 2-hydroxyethylamino.

5. The veterinary and pharmaceutical composition of claim 3 wherein Z is 2-hydroxypropylamino.

6. The veterinary and pharmaceutical composition of claim 2 wherein Y is

7. The veterinary and pharmaceutical composition of claim 6 wherein R is hydrogen and Z is 2-hydroxyethylamino.

8. The veterinary and pharmaceutical composition of claim 6 wherein R is hydrogen and Z is benzylidenehydrazino.

9. The veterinary and pharmaceutical composition of claim 6 wherein R is methyl and Z is $-\text{NNHNH}_2$.

10. The veterinary and pharmaceutical composition of claim 6 wherein R is hydrogen and Z is $-\text{NNNH}_2$.

11. A method of inducing a depressant response in mammals comprising administering to said mammal in need thereof an effective dosage of a compound of the formula

wherein Y is

wherein R is hydrogen; alkyl of 1-3 carbon atoms; hydroxyalkyl of 1-3 carbon atoms;

where m is 1-3;

wherein R' is hydrogen or hydroxyalkyl of 1-3 carbon atoms;

or

where alkylene is alkylene of 1-3 carbon atoms; and Z is $-\text{NH-alkylene-OH}$ where alkylene is alkylene of 1-4 carbon atoms;

where alkylene is alkylene of 1-4 carbon atoms and alkyl is alkyl of 1-3 carbon atoms;

$-\text{NH}-\text{N}=\text{CH}_2\text{R}_3$ where R_2 is hydrogen or alkyl of 1-3 carbon atoms and R_3 is alkyl of 1-3 carbon atoms, phenyl or nitrophenyl;

$-\text{NNHNH}_2$;

where R_4 is carboxyalkyl of 2-5 carbon atoms, alkyl of 1-3 carbon atoms, phenyl, carboxy- α -alkenyl of 3-5 carbon atoms, dialkylamino of 2-6 carbon atoms or alkoxy carbonylalkyl of 3-7 carbon atoms and alkylene is alkylene of up to 3 carbon atoms;

$-\text{NH-alkyl}$ where alkyl is alkyl of 1-3 carbon atoms; CCl_3 ;

$-\text{NH-alkylene-Cl}$ where alkylene is alkylene of 1-3 carbon atoms;

$-\text{O-alkylene-N-(alkyl)}_2$ where alkylene and alkyl have from 1-3 carbon atoms;

where each alkyl is of 1-3 carbon atoms;

where alkylene and alkyl have from 1-3 carbon atoms;

and

where alkylene is of 2-4 carbon atoms; and the salts thereof.

12. The method of claim 11 wherein

where R is hydrogen, alkyl of 1-3 carbon atoms or hydroxyalkyl of 1-3 carbon atoms; and Z is $-\text{NHR}_1-\text{OH}$ where R_1 is alkylene of 1-3 carbon atoms;

where alkyl is of 1-3 carbon atoms;

where R_2 is carboxyalkyl of 2-5 carbon atoms and alkylene is of 1-3 carbon atoms; or dialkylamino of 2-4 carbon atoms; and salts thereof.

13. The method of claim 12 wherein said compound is administered orally to said mammal.

14. The method of claim 12 wherein said compound is administered parenterally to said mammal.

15. The method of claim 12 wherein Y is

and Z is $-\text{NHR}_1\text{OH}$.

16. The method of claim 15 wherein Z is 2-hydroxyethylamino.

17. The method of claim 15 wherein Z is 2-hydroxypropylamino.

18. The method of claim 12 wherein Y is

19. The method of claim 18 wherein R is hydrogen and Z is 2-hydroxyethylamino.

20. The method of claim 18 wherein R is hydrogen and Z is benzylidenehydrazino.

21. The method of claim 18 wherein R is methyl and Z is $-\text{NHNH}_2$.

22. The method of claim 18 wherein R is hydrogen and Z is $-\text{NHNH}_2$.
